CLAIM

We claim the ornamental design for a display screen or
portion thereof with a graphical user interface, as shown and
described.

DESCRIPTION

The FIGURE is a front view of a display screen or portion
thereof with a graphical user interface showing our new
design.

The outermost broken line rectangle illustrates a display
screen or portion thereof and forms no part of the claimed
design. The remaining broken lines illustrate portions of the
graphical user interface that form no part of the claimed
design.
